UNITED STATES PATENT OFFICE.

EUGENE J. McCARTHY, OF NEW YORK, N. Y.

MASSAGING APPARATUS.

975,702.

Specification of Letters Patent. Patented Nov. 15, 1910.

Application filed March 28, 1910. Serial No. 551,986.

To all whom it may concern:

Be it known that I, EUGENE J. McCARTHY, a citizen of the United States, residing at New York city, in the county of New York, State of New York, have invented certain new and useful Improvements in Massaging Apparatus; and I do hereby declare the following to be a full, clear, and exact description of the invention, such as will enable others skilled in the art to which it appertains to make and use the same.

This invention relates to massaging apparatus, more particularly to apparatus of this character employed for imparting massaging action to portions of the face, and has for one of its objects to provide a simply constructed apparatus whereby a massaging action may be produced through the operation of suitably arranged pull cables, the pull cables being located in convenient position for manipulation by the hands of the wearer.

Another object of the invention is to provide an improved construction of the friction imparting feature of the apparatus which is flexible in all directions and adapts itself to the contour of the face.

With these and other objects in view, the invention consists in certain novel features of construction as hereinafter shown and described and then specifically pointed out in the claims.

The improved apparatus is designed more particularly for use beneath the chin, but may be employed upon other parts of the body if preferred, but for the purpose of illustration is shown arranged for use upon the face beneath the chin, for removing superfluous flesh.

In the drawings illustrating the preferred embodiment of the invention, Figure 1 is a side elevation of the improved apparatus applied, Fig. 2 is a front elevation of the same, Fig. 3 is a plan view, enlarged, of the chin engaging portion of the device or flexible massage member, Fig. 4 is a detail of one of the pads which engage the temples of the wearer, Fig. 5 is a view similar to Fig. 1 on a reduced scale illustrating a modification in the manner of operating the device. Fig. 6 is an enlarged detail illustrating the construction of a portion of the flexible massage member.

The improved apparatus comprises in general a flexible massage member carrying a

plurality of rotating massage balls, guide cables adapted to be supported upon the person of the wearer, and pull cables connected to the flexible massage member and leading over the pulleys. The flexible massage member consists of end frames each consisting of a plate 10 having ears 11 extending inwardly therefrom at the ends and with a cylindrical member 12 extending above the plate. The plates with their ears will be located at the ends of the flexible massage member and with the ears directed inwardly, and connected at their ends within the ears are flexible side members 13-14, preferably formed of leather or like material. A rod 15 is extended through each opposite pair of the ears and likewise through the portion of the side members which are located between the ears, as shown, to rigidly couple the end frames to the side members. Each of the plates 10 is provided with an outwardly directed headed pin 16 to receive the pull cables 17 as shown. The side members 13-14 are arranged to curve outwardly in opposite directions and are maintained in separated position by a plurality of shafts 18 spaced apart and of varying lengths so that the side members are supported in an elongated elliptical form, as shown in Fig. 3. Each of the shafts 18 is provided with an enlargement at the ends, one of which is represented at 19, and with a flange 20 bearing against the inner faces of the members 13-19 and thus maintaining the members in their distended position. By arranging the shafts 18 of varying lengths as shown in Fig. 3, the sides are maintained in symmetrical shape, as shown.

Mounted for rotation upon the shafts 18 are the friction producing balls 21 of any suitable material, but preferably of ivory, celluloid, or similar material. The number of the balls upon the shafts vary with the length of the shaft, as shown, the three shafts nearest the center being each provided with four of the balls and the next two shafts toward the ends being provided with three balls each, the next pair of shafts being provided with two balls each, and the terminal shafts provided with one ball each only. By this means the balls are arranged to practically fill the whole area between the side members, and are substantially uniformly spaced apart. Certain of the shafts are provided with sleeves between the balls thereon, as represented at 22, to maintain the

balls in suitable spaced relations, and thus cause the balls which are located upon the shafts which are provided with the spacers, to be maintained in position opposite the 5 spaces between the adjacent balls, so that the continuity of the balls is somewhat broken to cause the surface upon which they are designed to be more uniformly acted upon, as will be obvious.

10 Each of the enlargements 19 of the shafts is provided with a small clamp bolt or threaded pin 23 entered therein from outside the members 13—14 to prevent the latter from outward movement. By this means 15 the members 13—14 are firmly clamped in position upon the shafts, while at the same time their flexibility is not interfered with.

The guide pulley supporting portion of the device comprises a metal plate 24 which 20 bears over the head of the wearer, and connected to this curved plate at its lower end is a strap 25 which bears around the head of the wearer as shown in Figs. 1, 2 and 5. The strap 25 is preferably of leather and 25 arranged with one end terminating centrally of the front and connected to another strap 27 for extending over the head of the wearer and connected at its end to the strap 25 at the back. The strap 27 is also coupled to 30 the center of the metal band 24, as shown. The other terminal of the strap 25 overlaps the first mentioned terminal at the front, and is provided with means for adjustably coupling the terminals of the strap so that the 35 band may be adapted to heads of various sizes. Any suitable coupling means may be employed, but for the purpose of illustration a pair of pins 28 are shown attached to the strap 25 and the free end of the strap 40 25 is provided with a plurality of spaced apertures 29 adapted to fit over the pins 28. One of the pins 28 is shown employed as the securing means between the straps 25 and 27.

The band 24 is coupled to the strap 25 at 45 the lower edge of the latter only, as shown at 30 in Fig. 4, and connected at 31 to the strap 25 near its upper edge and opposite the band 24 are pads 32 which bear against the head of the wearer about opposite his 50 "temples." The band 24 is bent inwardly as shown at 33 in Fig. 2 just above the pads 32, so that a space is left for the pads, while at the same time the upper portion of the band 24 bears closely upon the head of the 55 wearer.

Connected to the band 24 near its ends are brackets 34 having cable guide pulleys 35 in their outer ends. The pull cables 17 lead over the pulleys 35 from the pins 16 60 and are provided with suitable hand grip devices 36, as for instance balls, as shown in Figs. 1, 2 and 5. The brackets 32 are set slightly oblique as shown in Figs. 1, 2 and 5, so that the cables operate without lateral 65 cramping. Each of the pull cables is pro-

vided with a suitable button 37 of suitable construction, to limit the movement and prevent the cables from being drawn entirely through the brackets 32.

In applying and operating the device the 70 band 24 is placed over the head and the strap 25 passes around the head with the pads 32 in position against the temples and the strap drawn relatively tight and secured by engaging the apertures 29 over the pins 75 28. The pull cables 17 are then connected to the pin 16 of the friction applying massage member and the latter located beneath the chin as shown in Figs. 1, 2 and 5. The grip members 36 are then grasped by the 80 hands of the wearer and motion applied alternately to move the friction imparting portion back and forth beneath the chin. The speed and the degree of pressure applied may be readily controlled by the operator, as will be obvious.

With a device thus constructed the chin portion of the face may be vigorously massaged, and the severity of the treatment readily controlled by the operator, as the 90 friction may be readily increased or decreased and the motion imparted as briskly or as lightly as required. If required a guard cloth or fabric may be worn between the face and the balls 21, to protect the face, 95 but this feature is not a part of the present invention, and its employment is so obvious that it is not deemed necessary to illustrate it. If required the pull cables 17 may be conducted over stationary pulleys located 100 on a wall or ceiling similar to ordinary exercising pulleys employed in sanitariums and gymnasiums as illustrated in Fig. 5, but this arrangement does not affect the invention and is not a departure from the principle 105 of the invention.

While two means for employing the device are illustrated, it will be understood that the invention is not necessarily limited thereto, as various changes and modifications within the scope of the appended claims may be made without departing from the principle of the invention.

What is claimed is:

1. A device of the class described comprising a band adapted to bear over the head, guide pulleys carried by said band, a flexible massage member, and draw cables connected to said flexible massage member and extending over said pulleys.

2. A device of the class described comprising a band adapted to bear over the head, a strap connected to said band and adapted to bear around the head, guide pulleys carried by said band, a flexible massage member, and draw cables connected to said flexible massage member and extending over said pulleys.

3. A device of the class described comprising a band for bearing over the head,

5 pads connected to said band, brackets extending from said band and having cable guide pulleys, a flexible massage member, and draw cables connected to said flexible massage member and extending over said pulleys.

10 4. A device of the class described comprising a band for extending over the head, a strap connected to said band for bearing around the head, another strap connected at its ends to said first mentioned strap and extending over the head and connected to the band, guide pulleys carried by said band, a flexible massage member, and draw cables connected to said flexible massage member and extending over said pulleys.

15 5. In a device of the class described, a flexible massage member comprising end frames having inwardly directed ears, flexible side members connected at their ends in said ears, a plurality of shafts spaced apart

and extending between said side members, balls mounted for rotation upon said shafts, a band for bearing over the head, guide pulleys carried by said band, and draw cables 25 connected to said end frames and leading over said guide pulleys.

6. In a device of the class described, a flexible massage member comprising end frames having inwardly directed arms, flexible side members connected at their ends in said arms, a plurality of shafts spaced apart and extending between said side members, and balls mounted for rotation upon said shafts. 30 35

In testimony whereof, I affix my signature, in presence of two witnesses.

EUGENE J. McCARTHY.
